UNITED STATES PATENT OFFICE.

WILLIAM WILSON LEE, OF NORTHAMPTON, MASSACHUSETTS.

OIL-DISTRIBUTING PROJECTILE.

SPECIFICATION forming part of Letters Patent No. 591,853, dated October 19, 1897.

Application filed December 9, 1896. Serial No. 615,075. (No model.)

To all whom it may concern:

Be it known that I, WILLIAM WILSON LEE, a citizen of the United States, residing at Northampton, in the county of Hampshire and State of Massachusetts, have invented a certain new and useful Projectile, of which the following is a specification, reference being had therein to the accompanying drawings.

My invention relates to that class of projectiles containing a reservoir for oil or other fluid, and designed to be fired or thrown by suitable guns or other contrivances, either from vessels or from on shore, for quieting heavy seas or breakers.

The object of my invention is to provide a projectile with a reservoir containing oil or other suitable fluid which may be fired or thrown a suitable distance ahead of a vessel, and so constructed that it will float and at the same time permit the oil to slowly flow from the reservoir into the water and thus smooth the heavy seas or produce a "slick," as it is called, so that when the vessel arrives at the point where the projectile is floating, or in its vicinity, the water will be practically quiet. By the use of a number of these projectiles at proper intervals it is obvious that the vessel may sail in comparatively smooth water as long as may be desired.

The invention consists, broadly, of a shell made of suitable material and a reservoir adapted to contain oil or other fluid, in combination with valve mechanism operating by the weight of the valve to open the reservoir, whereby when the shell is in the water the oil or other fluid is caused to flow outwardly from the reservoir and be distributed.

It also consists of the novel features of construction hereinafter set forth, and more particularly pointed out in the claims hereto appended.

Referring to the drawings, Figure 1 is a central longitudinal section of the projectile. Fig. 2 is a top plan view of the projectile with conical cap removed. Fig. 3 is a bottom plan view with steel cap removed; and Fig. 4 is a portion of a central section of the projectile inverted, showing the valve dropped from its seat.

Like letters refer to like parts throughout the several views.

a denotes the shell of the projectile, made

cylindrical in form and preferably of wood or some other suitable buoyant material.

b is a cap made preferably of lead, provided with inlet-holes *b' b'* and securely fastened to the upper portion of the shell *a*.

c is a conical-shaped cap made preferably of brass, provided with outlet-holes *c' c'* and securely fastened to the lower portion of the shell.

The holes *b' b'* and *c' c'* are preferably so constructed with reference to each other that the combined area of the holes *b' b'* are substantially equal to the combined area of the holes *c' c'*, in order that the oil may flow out of the holes *c' c'* substantially as rapidly as the water flows through the holes *b' b'*.

d is a rod made of any suitable material, though preferably made of brass, having a conical flanged portion *d'* near its base. This rod passes through the caps *b* and *c* and is free to move through the same to a limited extent, as hereinafter stated. The conical portion *d'* extends nearly to the inner circumference of the shell, and its function is substantially that of a valve having for its seat the conical portion *c*.

d' is a pin in the lower portion of the rod *d*, which, when the projectile is inverted, rests upon the conical-shaped cap *c* and arrests the downward movement of said rod.

e is a conical-shaped shell made preferably of brass or other suitable material soldered to the top of the rod *d*, forming the point of the projectile and covering the holes *b' b'* until forced downwardly, as hereinafter stated.

f is the base of the projectile and consists of a cap made of steel or other suitable material loosely or detachably connected with the lower portion of the shell *a* and cap *c*. The sides of this cap *b* are reinforced with copper *g* to prevent injury to the inside of the barrel of the gun when being fired.

The parts above described are preferably so constructed with relation to each other that when the shell is immersed in the water in an inverted position, as hereinafter stated, the bottom portion will float at or near the surface of the water.

When the projectile is not in use, it is placed upon its base, as shown in Fig. 1, the conical-shaped valve *d'* being seated upon the conical cap *c*, which prevents the oil or other fluid

from flowing out. When using the projectile, it is fired from any suitable gun or other means in the desired direction and to the point desired; the base or cap *f* receiving the impact of the blow of the explosion. This cap *f* being loosely connected with the shell drops off into the water in transit. The point of the shell being made of lead and heavier than its base strikes the water first and the shell plunges downwardly into the water for a short distance and then rises to the surface of the water in an inverted position, as shown in Fig. 4. The rod *d* by its own weight drops downwardly until arrested by the pin *d'*. This forces the point or cap *e* downward and unseats the valve *d'*, thus allowing the water to flow into the holes *c' c'* and force the oil slowly around the flanged portion *d'*, and out through the holes *b' b'*, and accomplishes the purpose desired.

I do not hereby intend to limit my invention to the precise construction above set forth and described, for it is obvious that the details of construction may be varied without departing from the spirit of my invention.

What I claim, and desire to secure by Letters Patent, is—

1. A projectile adapted to be thrown to a distance, comprising a shell, and a reservoir adapted to contain oil or other fluid and provided with a normally-closed inlet and an outlet passage, in combination with valve mechanism operated by weight of the valve itself for opening said reservoir.

2. A projectile adapted to be thrown to a distance comprising a shell, and a reservoir adapted to contain oil or other fluid and provided with a normally-closed inlet in its top portion and a normally-closed outlet in its bottom portion, in combination with valve mechanism operated by the weight of the valve itself for opening said reservoir.

3. A projectile adapted to be thrown to a

distance, comprising a shell, a reservoir adapted to contain oil or other fluid and provided with a normally-closed inlet and outlet passage, and an automatically-detachable base, in combination with valve mechanism for opening said reservoir. 45

4. A projectile adapted to be thrown to a distance comprising a shell, a reservoir adapted to contain oil or other fluid and provided with a normally-closed inlet and outlet passage, in combination with cap *b* provided with normally-closed inlet-hole *b'*, cap *c* provided with a normally-closed outlet-hole *c'*, rod *d* provided with valve *d'* for opening said reservoir only when the projectile is inverted. 55

5. A projectile adapted to be thrown to a distance comprising a shell, a reservoir adapted to contain oil or other fluid and provided with a normally-closed inlet and outlet passage, in combination with cap *b* provided with a normally-closed inlet-hole *b'*, cap *c* provided with a normally-closed outlet-hole *c'*, rod *d* provided with valve *d'* and conical shell *e*. 60

6. A projectile adapted to be thrown to a distance, having an oil-reservoir; a reservoir-inlet toward the front end of the projectile and reservoir-outlet near the butt-end of the projectile; and means which control said inlet and outlet; one end of the projectile being weighted to cause the projectile to float the other end up, in the water, and the inlet 70 and outlet being then automatically opened to permit water to flow in the reservoir at the inlet to expel the oil therefrom at the outlet.

In testimony whereof I have signed my name to this specification, in the presence of two subscribing witnesses, on this 30th day of October, A. D. 1896.

WILLIAM WILSON LEE.
